UNITED STATES PATENT OFFICE.

EDWIN CALVIN, OF SQUANTUM, MASSACHUSETTS, ASSIGNOR TO BEARFOOT SOLE CO. INC., OF BOSTON, MASSACHUSETTS, A CORPORATION OF MASSACHUSETTS.

DESIGN FOR A SHOE SOLE.

Application filed December 8, 1926. Serial No. 19,981. Term of patent 7 years.

To all whom it may concern:

Be it known that I, EDWIN CALVIN, a citizen of the United States, residing at Squantum, in the county of Norfolk and Commonwealth of Massachusetts, have invented a new, original, and ornamental Design for a Shoe Sole, of which the following is a specification, reference being had therein to the accompanying drawing.

Figure 1 is a plan view of the shoe sole

showing my new design, and Figure 2 is a longitudinal sectional view of a portion of the sole on line 2—2 of Fig. 1.

I claim:

The ornamental design for a shoe sole, as shown.

In testimony whereof I hereunto affix my signature.

EDWIN CALVIN.
